DESIGN FOR A HANDLE FOR SPOONS, FORKS, OR SIMILAR ARTICLES.

No. 38,332.

Specification for Design.

Patented Dec. 4, 1906.

Application filed October 29, 1906. Serial No. 341,187. Term of patent 7 years.

To all whom it may concern:

Be it known that I, GILBERT L. CROWELL, Jr., a citizen of the United States, residing at Arlington, in the county of Hudson and State of New Jersey, have invented a new, original, and ornamental Design for Handles for Spoons, Forks, and Similar Articles, of which the following is a specification, reference being had to the accompanying drawings, forming a part thereof.

Figure 1 is a plan view of the front or obverse side of the handle, showing my new de-

sign. Fig. 2 is a similar view of the reverse or rear side of the handle, the handle in both figures for the sake of clearness being shown in connection with the bowl of a spoon or the tines of a fork.

I claim—

The ornamental design for a handle for a spoon, fork or similar article as shown.
